[57] CLAIM

The ornamental design for a multi-layered cereal bowl, as shown and described.

DESCRIPTION

FIG. 1 is a top, front perspective view of a multi-layered cereal bowl showing my new design;

FIG. 2 is a top plan view thereof;

FIG. 3 is a front elevational view thereof;

FIG. 4 is a bottom plan view thereof;

FIG. 5 is a left side elevational view thereof; the right side view (not shown) is a mirror image thereof; and

FIG. 6 is a rear elevational view thereof.

FIG. 1

FIG. 2

FIG. 3

FIG. 4

FIG. 5

FIG. 6
